CLAIM

I claim the ornamental design for a building, substantially as shown and described.

DESCRIPTION

FIG. 1 is a perspective view of the building.

FIG. 2 is a front elevation view of the building as shown in FIG. 1.

FIG. 3 is a rear elevation view of the building as shown in FIG. 1; and,

FIG. 4 is a top plan view of the building as shown in FIG. 1.

The broken line disclosure is for illustrative purposes only and forms no part of the claimed design.
